UNITED STATES PATENT OFFICE.

JOHN DOUGLAS FRIER, OF WARINGSTOWN, IRELAND.

MACHINE FOR TEARING FABRICS.

Application filed July 19, 1922. Serial No. 576,136.

To all whom it may concern:

Be it known that I, JOHN DOUGLAS FRIER, a subject of the King of Great Britain and Ireland, residing at Waringstown, county 5 Down, Ireland, have invented certain new and useful Improvements in Machines for Tearing Fabrics, of which the following is a specification.

This invention relates to a machine for 10 tearing fabrics and applicable for the production of strips of cloth suitable, for example, for the manufacture of square or oblong articles such as handkerchiefs, pillow cases, etc.

15 Under my invention the fabric is led from a pile on a table, or a bar, or roller over and between guide bars or rollers and through a slot in a transverse plate with suitable guides where it is torn, one strip 20 being led to a winding roller or equivalent, at one side of the machine and the other strip to a winding roller, or equivalent, at the other side of the machine. The torn strips of cloth from the slotted plate are 25 led from guide rollers to rollers on a pivoted frame, passing under said rollers and upwards over other guide rollers to the winding rollers, the arrangement being the same at each side of the machine and such that 30 if more cloth is wound on to one winding roller than another, the pivoted frame will tilt upwardly at the end nearest to the roller taking the cloth quicker. This tilting of the frame may be used to operate a warning 35 bell, or equivalent, and to operate a stop motion whereby the machine will be stopped to allow of adjustment of the cloth coming from the tearing plate.

The cloth as it passes from the table, or 40 bar, or roller, is, preferably, first led over a guide roller, or bar, then under a second guide roller and back over the top of the first guide roller, then under a roller, supported on pivoted brackets, which roller 45 rests on the cloth in such position as to assist or add to the tensioning effect and when the tension of the cloth, moving in two directions over the first mentioned guide roller or bar is excessive the pivoted roller will

rise on its pivots and will thus ease the 50 tension.

The invention will now be described with reference to the accompanying drawings whereon:—

Fig. 1 is a side elevation of a cloth tearing 55 machine constructed in accordance with my invention.

Fig. 2 is a plan view corresponding to Fig. 1.

Figs. 3 and 4 are respectively side view 60 of the top portion and end view of the lower portion of the stop motion in accordance with the invention.

Referring to the drawings:—

The fabric 1 is supported by a bar 2 on a movable table 3 from which the fabric 1, after being nicked, is led round tension rollers 4, 5 and around a pivoted tension roller 6 and up between transverse bars 7 and 8 where it is torn. From the bars 7 and 8, 70 one end of the fabric 1 is led round rollers 9, 10 and 11 to a winding roller 12 at one end of the machine, the other end of the fabric being led round rollers 13, 14 and 15 to a winding roller 16 at the other end of 75 the machine. The rollers 10 and 14 are supported on a tilting frame 17 pivoted at 18 to the machine frame, the movement of the frame 17 being controlled by the take up of the fabric on the winding rollers so that if 80 one of the winding rollers takes up faster than the other, the frame 17, will tilt lower on the side which takes up the least fabric.

A lever 19 is pivotally supported at 20^a on one end of a plate 20, on which a transverse plate 21 is pivotally supported. The plate 21 is held from movement by the end 19^b of the lever 19 until released thereby. A slideable rod 22 is held from movement by the plate 21 until the latter is released by movement of the end 19^b of the lever 19. A bar 23 is pivotally supported on the plate 20 and presses against the slideable rod 22. A lever 24 is pivotally connected with the end 20^b of the plate 20 and is connected with one end of a link 25 whose other end is connected with the plate 20. Pivotally supported at 26^a is a lever 26 which is normally

held in position by a weight 27. One end of a member 28 is pivotally supported at 28^a, its other end 28^b engaging the end 29^a of a bar 29 on which the belt fork 30 is carried. The bar 29 is movable under the action of a spring 30^a. The arrangement is such that if the roller 12 is taking up more fabric than the roller 16, the left side of the frame 17 will rise; and, when it has risen 10 to its fullest extent it will cause the bar 10^a to come into contact with the end 19^a of the lever 19 and cause the end 19^b of the lever 19 to be moved and release the plate 21, thereby allowing the slidable rod 22 to be 15 pushed forward by the bar 23 into engagement with a cam 31 on the spindle 32 of the winding roller 12. The engagement of the slidable rod 22 with the cam 31 causes the rod 22 to be pressed down into engagement 20 with the end 26^b of the lever 26 thereby causing the end 26^a of the lever 26 to rise and lift the end 28^b of the lever 28, out of engagement with the end 29^a of the bar 29 which is then free to be moved by the spring 25 30^a and so change the belt on to the loose pulley and thereby stop the machine.

If the winding roller 16 is taking up more fabric than the roller 12 the bar 10^a will be caused to come into contact with the lever 30 24 and depress same and through the link 25 the end 19^b of the lever 19 will be pulled down and will release the plate 21 which will allow the rod 22 to be moved by the bar 23 into engagement with the cam 31 thereby 35 by causing the rod 22 to be depressed and to act in the manner as hereinbefore described and so stop the machine.

When it is necessary to resplit a width of fabric which has been split, the roller 40 containing the split fabric is supported on a spindle 33 carried by movable plates 34. The fabric in this case is first led under the pivoted tension roller 6, then over the roller 4 and round the roller 5 from which it is 45 led to the tearing bars 7 and 8.

Having now fully described my invention what I claim and desire to secure by Letters Patent is:—

1. A machine for tearing fabrics longitudinally, comprising a framework, a support for the fabric, a movable table carrying said support, a winding roller on each side of said support and carried by the framework, tensioning means for the fabric, transverse bars having a transverse slot therebetween where the fabric is torn by the pull of the winding rollers on each side thereof, a tilting frame interposed between the tearing bars and the winding rollers and round the 55 ends of which the fabric is led to the winding rollers, the position of the frame being determined by the take up of the winding rollers, and a stop motion which is brought 60

into action by the location of the tilting frame when it is tilted to a predetermined extent. 65

2. A machine for tearing fabrics longitudinally, comprising a framework, a support for the fabric, a movable table carrying said support, a winding roller on each side of 70 said support and carried by the framework, tensioning means for the fabric, transverse bars having a transverse slot therebetween where the fabric is torn by the pull of the winding rollers on each side thereof, a tilting frame interposed between the tearing bars and the winding rollers and round the 75 ends of which the fabric is led to the winding rollers, the position of the frame being determined by the take up of the winding rollers, a plate supported on the framework, a lever pivotally supported on the plate, a transverse plate also pivotally supported on the plate on the frame work and held from 80 movement by said lever until released by a movement of the lever, a bar pivotally supported on the plate on the framework and pressing against a slidably supported rod normally held out of the range of a cam, the 85 tilting of the frame causing the bar pressing on said rod to bring it into contact with the cam, which causes the slidable rod to be moved and in moving to operate a weighted lever held in normal position by a 90 weight and which when moved by the slidable rod effects the release of a spring controlled fork, which when released is moved by spring means so as to cause the driving 95 belt of the machine to be moved from the fast to the loose pulley. 100

3. A machine for tearing fabrics longitudinally, comprising a frame work, a support for the fabric, a movable table carrying said support, a winding roller on each side of 105 said support and carried by the framework, tensioning means for the fabric, transverse bars having a transverse slot therebetween where the fabric is torn by the pull of the winding rollers on each side thereof, a tilting frame interposed between the tearing bars and the winding rollers and round the 110 ends of which the fabric is led to the winding rollers, the position of the frame being determined by the take up of the winding rollers, a plate supported on the frame work, a lever pivotally supported on the plate, a transverse plate also pivotally supported on the plate on the framework and held from 115 movement by said lever until released by a movement of the lever, a bar pivotally supported on the plate on the frame work and pressing against a slidably supported rod normally held out of the range of a cam, the tilting of the frame causing the bar pressing on said rod to bring it into contact with the 120 cam, which causes the slidable rod to be 125

5 moved and in moving to operate a weighted lever held in normal position by a weight and which when moved by the slidable rod effects the release of a spring controlled fork, which when released is moved by spring means so as to cause the driving belt of the machine to be moved from the fast to the loose pulley, and means whereby the tilting of the frame at either end beyond a pre-

determined limit causes the operation of said 10 stop motion.

In testimony whereof I affix my signature in presence of two witnesses.

JOHN DOUGLAS FRIER.
